(57) **CLAIM**

The ornamental design for a video eyewear device, as shown and described herein.

DESCRIPTION

FIG. 1 is a front perspective view of a first embodiment of the video eyewear device showing my design;

FIG. 2 is a top view of the video eyewear device shown in FIG. 1;

FIG. 3 is a rear elevation view of the video eyewear device shown in FIG. 1;

FIG. 4 is a left side elevation view of the video eyewear device shown in FIG. 1;

FIG. 5 is a front elevation view of the video eyewear device shown in FIG. 1;

FIG. 6 is a right side elevation view of the video eyewear device of FIG. 1;

FIG. 7 is a bottom view, which is a mirror image of the top view, of the video eyewear device of FIG. 1;

FIG. 8 is a front perspective view of a second embodiment of the video eyewear device showing my design;

FIG. 9 is a top view of the video eyewear device shown in FIG. 8;

FIG. 10 is a rear elevation view of the video eyewear device shown in FIG. 8;

FIG. 11 is a left side elevation view of the video eyewear device shown in FIG. 8;

FIG. 12 is a front elevation view of the video eyewear device shown in FIG. 8;

FIG. 13 is a right side elevation view of the video eyewear device of FIG. 8; and,

FIG. 14 is a bottom view, which is a mirror image of the top view, of the video eyewear device of FIG. 8.

The broken lines shown in FIGS. 1 through 14 illustrating various ornamental and functional features of the device including the earpiece section of the device represent environmental elements only and form no part of the claimed design.

1 Claim, 10 Drawing Sheets
